BOX HEAD LABELER

Melvin W. Flynn, San Francisco, Calif.

Application June 19, 1945, Serial No. 600,295

11 Claims. (Cl. 216—52)

1

An object of my invention is to provide a box head labeler that is automatic in operation, the device removing one shoox at a time from a feed magazine and applying a label to the shoox before transferring it to a stacker. All the operator needs to do is to supply unlabeled shooxs to the feed magazine and to remove labeled shooxs from the stacker. He must also keep a stack of labels on the label-supporting platform.

A further object of my invention is to provide a device of the type described in which means is provided for accommodating shooxs of different sizes and thicknesses and for accommodating labels of different sizes.

A still further object of my invention is to provide a device in which a label is fed to the label applying means only when a shoox is in position to receive the label.

Other objects and advantages will appear in the following specification, and the novel features of the device will be particularly pointed out in the appended claims.

My invention is illustrated in the accompanying drawings forming a part of this application, in which:

Figure 1 is a side view of the entire machine; Figure 2 is a top plan view of the machine;

Figure 3 is a side elevation of the opposite side of the machine from that shown in Figure 1;

Figure 4 is a longitudinal section through the entire machine and is taken substantially along the line 4—4 of Figure 2;

Figure 5 is a transverse section on an enlarged scale taken along the line 5—5 of Figure 4;

Figure 6 is an enlarged side elevation of the portion of the machine shown in Figure 5, the arrows 6—6 on Figure 5 indicating from which side the machine is viewed;

Figure 7 is an enlarged sectional view of the shoox stacker mechanism taken along the line 7—7 of Figure 2, and shows the stacker table in lowered position;

Figure 8 is a view similar to Figure 7, but shows the stacker table in raised position;

Figure 9 is an enlarged detail of a portion of the stacker when looking in the direction of the arrows 9—9 in Figure 7, and sets forth one of the shoox supporting dogs;

Figure 10 is an enlarged transverse section taken along the line 10—10 on Figure 4 and shows the label arresting and positioning mechanism;

Figure 11 shows an enlarged view of a portion of the label arresting and positioning mechanism and is taken substantially along the line 11—11 of Figure 10 with the nearest frame side removed and the cam being indicated at its high point;

Figures 12 and 13 are views similar to Figure 11, Figure 12 showing the cam at the half-way

2

point, and Figure 13 illustrating the cam at its low point;

Figure 14 is an isometric view of the shoox supporting dogs; and

Figure 15 is an isometric view of the stacking table.

While I have shown only the preferred forms of my invention, it should be understood that various changes or modifications may be made within the scope of the appended claims without departing from the spirit and scope of the invention.

In carrying out my invention, I provide a main supporting frame indicated generally at 1 and this frame has a shoox feeding magazine 10 at one end and a stacker magazine for receiving labeled shooxs disposed at the other end. Unlabeled shooxs 56 are placed in the feed magazine 10 and are delivered to the stacker magazine by a mechanism now to be described, the shooxs in passing from the feeder to the stacker having labels applied thereto.

I will first describe the feed magazine. In Figure 4 it will be noted that the magazine comprises a shoox-receiving hopper indicated generally at 18 and the hopper has a bumper plate 11 at one end and spaced flushing plates 13 at the other end. The shooxs are manually fed into the hopper and abut the bumper plate 11 and then they are lowered into position. The opposite edges of the shooxs strike the curved portions of the flushing plates 13 and are brought into proper register so that the shooxs will be horizontally arranged and will be aligned one above the other in the hopper. The bumper plate 11 is held in place by both sides of the main supporting frame 1. The bumper plate 11 is provided with slots for bolts 12 so that the hopper side members 10a may be adjusted toward or away from each other to accommodate shooxs of different lengths. Figure 4 shows the flushing plates 13 secured to the side members 10a by bolts 14, which may be adjusted forward or backward in slot 14a to accommodate different widths of shooxs.

The lowermost shoox in the hopper 10 rests on a carrier 6 that extends throughout the greater length of the machine. Figure 10 shows the carrier 6 as being angle bars. Endless chains 5 are mounted on sprockets 4 and 4a disposed at opposite ends of the carrier 6 and the sprockets in turn are mounted on shafts 2 and 2a that are rotably carried by the sides of the frame 1. The upper reaches of the chains 5 ride in the angle bars of the carrier 6. Referring to Figure 4, it will be seen that a motor and reduction gears, indicated generally at 3, are operatively connected to the shaft 2a by a sprocket chain or belt, indicated generally at 2b. A connecting of the motor 3 to a source of current will cause the sprocket chain 2b to move the endless chains 5.

There are two sprockets 4 mounted on the shaft 2, and two sprockets 4a mounted on the shaft 2a. There are two endless chains 5 which are passed around the pairs of sprockets and the chains 5 act as timing chains. Each chain 5 carries a plurality of lugs 9 and these lugs engage the lowermost shoo in the hopper 10, and remove it from the hopper and move it along the carrier 5. In this way one shoo at a time is removed from the bottom of the stack 10 of shooes.

The carriers 6 are fastened to the transverse angles 7, which are attached to the sides of the frame 1. Lugs 6a on the carriers 6 receive bolts 8 which also pass through slots 7a in the transverse angles. The carrier 6 may be adjusted laterally in the manner to accommodate various sized shooes. The sprockets 4 and 4a may be moved laterally by loosening their set screws.

I will now describe the mechanism for applying a layer of adhesive to the upper surface of each shoo as it is moved by the chains 5 along the carrier 6. Again referring to Figure 4, it will be noted that I provide a receptacle 17 for holding a quantity of adhesive. This receptacle is positioned adjacent to the bumper plate 11. A rubber roller 16 mounted on a shaft 85 has the lower portion of its periphery immersed in the adhesive so that a rotation of the roller in a counterclockwise direction as shown will cause the roller to pick up adhesive on its periphery. A scraper 18 is adjustably positioned with respect to the periphery of the roller 16 by bolts 19 so that a layer of a given thickness will remain on the roller as the periphery portion passes the scraper.

A second rubber roller 15 contacts with the periphery of the first roller 16 and also contacts with the upper surface of a shoo 56 which passes under the roller 15. The peripheral speed of the roller 15 is the same as the forward moving speed of the shoo and therefore a uniform layer of adhesive will be applied to the entire upper surface of the shoo.

The particular mechanism for rotating the rollers 15 and 16 is shown in Figure 3. The shaft 85 projects through one side of the frame 1 and has a sprocket 86 mounted thereon. The roller 15 is mounted on a shaft 88 that has a sprocket 89 mounted thereon. A sprocket chain 87 passes around the sprockets 86 and 89 in the manner shown and this chain also passes around a sprocket 90 and a sprocket 91 for a purpose hereinafter described.

The sprocket 91 is mounted on a shaft 31 and this shaft has a sprocket 32 mounted thereon as shown in Figure 4 and disposed on the inner side of the frame 1. The sprocket 32 on shaft 31 is operatively connected to the shaft 2 by a sprocket chain 33 and a sprocket 4b on shaft 2 similar to the sprocket 4, see Figure 2. In this way continuous rotational movement is imparted to the rollers 15 and 16.

After the shoo receives a layer of adhesive on its upper surface, the shoo passes on and receives a label. I will now describe the label feeding mechanism and will set forth the means for preventing a label from being fed until there is a shoo in position to receive the label. Again referring to Figure 4, it will be seen that I provide a feeder table 20 adjacent to the rollers 15 and 16 and this table extends between the sides of the frame 1. On the table 20 I dispose a plurality of labels 21. These labels are removed one at a time by a mechanism that

will feed a label for each shoo that has previously been coated with a layer of adhesive on its upper surface.

Referring to Figures 4 and 6, it will be seen that an arm 23 is mounted on a sleeve 24 and this arm has a pair of friction pads 75, see Figure 5, mounted in casings 76 which in turn are pivotally secured to the free end of the arm 23 by pins 77a. The friction pads 75 rest on the uppermost label 21 and therefore a movement of the arm 23 to the left in Figure 4 will remove the uppermost label from the stack of labels supported by the table 20.

The arm 23 is reciprocated in a longitudinal direction by a slide 36, see Figures 1 and 6. The sleeve 24 is rockably mounted on a rod 25 which extends through a slot 36a in the side of the frame 1. Rollers 37 are carried by the same frame side and are received in slots 37a provided in the slide 36. This arrangement will hold the slide 36 in a horizontal position during its reciprocation by a mechanism now to be described.

A lever 35, see Figure 6, is pivotally mounted on the side of frame 1 at 39 and the lever has a slot 35a at its upper end for receiving the end of the rod 25 that projects through the frame and through the slide 36, to which it is rigidly attached. The lever is rocked about the pivot 39 by a pin 77 on a sprocket 40. As the sprocket 40 rotates in a counterclockwise direction, the lever 35 is actuated for reciprocating the slide 36 and the arm 23.

I provide means for causing the arm 23 to have its friction tabs 75 engage with the uppermost label 21 when the arm is moved to the left in Figures 4 and 6 and to be raised above the stack of labels on its return movement. It will be seen that the sleeve 24 is rockably mounted on the rod 25 which in turn is reciprocated by the slide 36. The sleeve 24 receives its reciprocatory movement by the reciprocation of the slide 36, but the sleeve is rocked on its supporting rod 25 by an arm 26 that is rigidly secured thereto and carries a roller 27 at its free end, this roller riding on a horizontal portion of a vertical movable cam follower 28.

Figure 6 shows the cam follower provided with vertically extending slots 28a that receive guide pins 28b, which in turn are carried by the inner side of the right-hand frame member 1 shown in Figure 5. The sprocket 40 is mounted on the shaft 31 and the same shaft carries a cam 30. A cam roller 29, carried by the lower end of the cam follower 28, rides on the cam 30 and the high point of the cam 30 is so arranged with respect to the position of the pin 77 upon the sprocket 40 that as soon as the arm 23 completes its movement to the left in Figure 6 for removing the uppermost label, the high point of the cam 30 will raise the cam follower 28 and swing the arm 26 in a clock-wise direction for swinging the arm 23 in the same direction and raising the rubber pads 75 above the stack of labels. The cam 30 will hold the cam follower 28 in this raised position during the return movement of the arm 23. The cam 30 will permit the cam follower 28 to lower just before the arm 23 starts its next movement to the left and this will bring the rubber pads 75 into engagement with the next label for removing this from the pile or stack of labels.

It will be seen from Figures 5 and 6 that the cam 30 has an auxiliary portion or adjustment member 41 mounted on the same shaft 31 and adjustably connected to the cam 30 by a bolt

42. The adjustment member 41 has an arcuate slot that receives the bolt 42 and this permits the member to be adjusted angularly with respect to the cam for altering the time at which the cam follower 28 will permit the arm 23 to lower. This feature adapts the device to handle labels of different widths.

I also provide means for preventing the arm 23 from removing a label when the machine fails to move a shook into a position to receive the label. Again referring to Figure 5, it will be seen that I provide an auxiliary shaft 45 that is rockably mounted between the sides of the frame 1. This shaft carries an arm 43 which in turn supports a roller 44 and is placed in the path of the shook 56. When a shook is in position to receive the label, the arm 43 will be rocked downwardly by the shook engaging with the roller 44 and the rocking movement of the arm will cause the shaft 45 to rock a second arm 46 and to move the free end of the latter arm out from under a projection 28c carried by the cam follower 28. When the arm 46 frees the projection 28c, the cam follower 28 can move downwardly as the cam 30 revolves. Should no shook be present to receive a label, the arm 43 will remain in raised position and the arm 46 will hold the cam follower 28 in raised position. This will keep the arm 23 in raised position during its movement to the left in Figure 6. The pads 75 will be held in spaced relation above the top label and no label will be removed. A torsional spring 73 is used for yieldingly holding the arm 43 in raised position.

The sprocket 40 is rotated by the shaft 31. Figure 3 shows the shaft 31 carrying the sprocket 91. As already stated, the shaft 31 is rotated by the sprocket 32 and chain 33. The timing is such that one label will be removed from the stack of labels for each shook that passes over the arm 43.

In Figure 4 I show how the label is conveyed from the stack of labels to endless conveyor belts 22 which are passed around a shaft 84 and around a second shaft 67. The shaft 84 is rotated by the sprocket 90 and by the chain 87, see Figure 3. The upper reaches of the belts 22 are inclined downwardly at an angle so as to carry the label toward the shook that has received a layer of adhesive. The shaft 84 has contacting rollers 82 mounted on a shaft 83 so that when the label is fed between the rollers 82 and the shaft 84 by arm 23, the label will be carried forward by the rollers 82 and belts 22.

I provide novel means for holding the label 21 in position for the shook and to align it with the shook as it passes under the shaft 67. In Figure 11 I show a shaft 60 that carries guide holders 62 and these guide holders have guides 63 adjustably mounted thereon and held in place by bolts 64. The lower ends of the guides 63 are set slightly above the upper surface of the shook 56. Figure 10 shows the shaft 60 supported by the sides of the frame 1. The portion of the shaft 60 projecting beyond the left-hand side of the frame 1 in Figure 10 carries an eccentric 61 and an eccentrically mounted pin 69. A tripping arm 47 is mounted on the shaft 51 on the left side of the frame 1 and has a hook 47a designed to engage with the pin 69. Figure 10 shows the shaft 51 supported by the frame 1 and carrying an arm 57 on the right side of the frame. The arms 47 and 57 carry a shaft 65 and the sides of the frame 1 are slotted to permit a swinging movement of the shaft 65 toward and away from the shook 56. The shaft 65 carries rubber rollers 66 that are

normally disposed above the top of the shook and above the label 21 that is in a position to be applied to the shook. Strips 68 guide the label 21 from the shaft 67 to a point adjacent to the stop guides 63.

The tripping arm 47 and the arm 57 are controlled by a cam roller 52 that is mounted on an integral extension of the arm 47. The roller 52 contacts a cam 48 which is adjustably secured to a sprocket 53 by bolts 49. The sprocket 53 is rotated by a sprocket chain 50 that is passed around the sprocket 40 so that the movement of the arms 47 and 57 will be in accordance with the movement of the arm 23.

The timing is such that the high point of the cam 48 will engage the cam roller 52 to keep the rollers 66 above the strips 68 until a label 21 is fed to the stop guides 63, see Figure 11. When the shook 56 reaches a position adjacent to the stop guides 63, as in Figure 12, the cam roller 52 will be moving from the high point on the cam to the low point and a spring 54 connected to the tripping arm 47 and to a bolt 55, urges the arms 47 and 57 into a position where the roller 66 will press the label 21 down upon the shook 56. As this movement of the tripping arm 47 takes place, the hook-shaped end 47a will contact with the pin 69 and will rock the shaft 60 for swinging the guide stops 63 away from the end of the label as shown in Figure 13.

The length of the arm 47 is much greater than the length of the eccentric 61, so that the stop guides 63 will be quickly moved out of place. The rollers 66 are now yieldingly held down upon the label 21 and will press the label upon the upper surface of the shook that has already received a layer of adhesive. The label will therefore be properly applied on the shook. At the completion of applying the label to the shook, the high point of the cam 48 will again swing the cam follower 52 and cause the arms 47 and 57 to raise the rollers 66 into the position shown in Figure 11 and this will permit the stop guides 63 to return to their vertical position by means of gravity and be ready to stop and position the next label.

In Figure 4 I show a rubber roller 94 for pressing the label down upon the shook and for smoothing out any wrinkles. The roller 94 is mounted on a shaft 95 and Figure 3 shows the shaft carrying a sprocket 96 that meshes with a sprocket chain 93. The sprocket chain 93 is passed over a sprocket 92 that is mounted on the shaft 2a. The chain 93 also passes over a sprocket 71 that is rotatably mounted on the shaft 51 and around a sprocket 97 that is mounted on a shaft 98.

I will now describe the mechanism for moving one labeled shook at a time into the shook stacker. Figure 4 shows the shaft 98 carrying a cam 99, see also Figures 7 and 8. A stacker table 107 is disposed at a point to receive a labeled shook when a cam roller 114 rides on the low point of the cam 99. The cam roller 114 is mounted on a pin 115 which in turn is secured to a vertically movable arm 111 that is square in cross section. The arm slides in a bearing 112 that has a square bore and the top of the arm supports the platform 107.

The platform 107 is shown in Figure 15 and it will be seen that the platform has angle plates 109 adjustably secured to the platform by bolts 110. The plates can be positioned to support shooks of different sizes. The shooks are moved by the chains 5 so as to rest on the tops of the angle plates 109. Only one shook is received at 75 a time.

After a shook has been moved onto the table 107 while the latter is in its lower position, the cam 99 will raise the table to lift the shook into the dotted line position shown in Figure 8. The stacker carries vertically extending angle-shaped corner members 117 and 118 and the shook is lifted so as to be received between these corner members or arms. Each pair of members 117 and 118 carry spring-pressed dogs 116, see Figure 9, these dogs being held in closed position by leaf springs 119 that are secured to the angle by bolts 120.

Figure 14 shows a perspective view of one of the dogs 116 and the dog is free to slide in a slot 116a provided in the arm and the spring yieldingly holds the dog so that it will project into the recess formed by the arm. As the shook is raised by the platform 107, the dogs 116 will be moved outwardly and then when the shook clears the dogs, the springs 119 will snap them back into a position to support the shook. The cam 99 can now lower the platform to receive the next shook. The stacker is supplied with shooks one at a time by the platform for each rotation of the cam 99. The timing of the cam is such that the platform will be raised once for each time a shook is received.

From the foregoing description of the various parts of the device, the operation thereof may be readily understood.

The unlabeled shooks are placed in the hopper 10 and the size of the hopper is adjusted to accommodate the size of the shook. Figure 1 also shows the motor 3 mounted on a base plate 103 and secured to longitudinally extending bars 104 by bolts 102. The rods 105 connect the sides of the frame 1 together and receive nuts 106.

The shooks are fed one at a time from the hopper 10 to the endless chain 5 and the lugs 9 on the chains 5 to remove the lowermost shook from the stack. The top surface of each shook is given a layer of adhesive by the roller 15 and when the shook reaches a position adjacent to the stop guides 63, a label 21 is applied to the shook by the rollers 66. I have already set forth the mechanism that prevents a label from leaving the strips 68 until a shook 56 is in a position to receive the label. The movement of the arm 23 and the rubber pressure pads 78 can be adjusted to accommodate labels of different sizes and the stop guides 63 can be vertically adjusted to accommodate shooks of different thicknesses. After the label is applied to the shook, a roller 94 presses the label on the shook, smooths out any wrinkles, and removes any air pockets that may prevent the label 21 from adhering to the shook.

The labeled shook is delivered by the chains 5 and lugs 9 to the stacker table 107 when the latter is in its lowermost position. The cam 99 raises the table and forces the shook above the dogs 116, which move into inoperative position to permit the shook to pass and then snap back into operative position to support the shook. The stacker can hold a large number of labeled shooks and these can be removed by an operator as needed.

The angle members 117 and 118 of the stacker are adjustable to accommodate shooks of the desired size. Figure 2 shows the angle members 117 provided with lugs 122 and bolts 123 for securing the lugs in adjusted position on a transversely extending angle bar 121. The bar has slots 123a for receiving the bolts 123. The sides of the stacker angles paralleling the sides of the frame 1 extend below the angle bar 121 and are curved

outwardly at 117a, see Figures 7 and 8, to guide the shook 56 laterally as the shook is moved upwardly should this be necessary.

The stacker angles 118 have lugs 126 that rest on a transversely extending bar 124 and the bar has slots 127 for receiving bolts 125 for supporting the stacker angles in adjusted position. Figure 2 shows the sides of the stacker angles that parallels the sides of the frame 1 as being flared outwardly as shown at 128 and the flared portions face the shook 46 as it moves over the chains 5 onto the platform 107. The flared ends 128 adjust the shook laterally during the substantially horizontal and longitudinal movement of the shook onto the platform 107.

In Figures 2 and 3 I show the ends of the bar 124 extending at right angles and connectable to the sides of the frame 1 by bolts 129. The sides of the frame 1 have a plurality of openings 130 for receiving the bolts 129 and this permits the bar 124 to be adjusted toward or away from the bar 121, to accommodate different size shooks.

The adjustment member 41, see Figure 6, adapts the arm 23 to handle labels of different sizes. Some labels may be only two inches wide and under such a condition, the arms 23 will contact the label and move it about one inch. The larger the size of labels used, the greater the number that can be stacked on the feeder table 28. The peripheral speed of the rollers 66 will be the same as the forward speed of the shook. Thus the label is pressed smoothly upon the shook without any tendency of the label turning or being applied unevenly to the shook. The shaft 65 is revolved by the meshing gear 59 mounted thereon, and the gear 58, attached to the gear 71, is rotatably mounted on the shaft 51. The peripheral speed of all rollers that come into contact with the shooks, as they are carried along the endless chains 5 by lugs 9, will be the same as the forward speed of the shook, to eliminate any unnecessary wear or friction.

I claim:

1. In a machine of the type described, a member for holding a stack of labels, a reciprocable arm for removing one label at a time from the stack, label-conveying means for receiving the removed label, label-positioning and holding means cooperating with the label-conveying means for holding the label in a predetermined position, means for moving a shook under the label-holding means, and including means for releasing the label-holding means from the label when the shook is in a position to receive the label, and means for pressing the label down upon the shook.

2. In a machine of the type described, a member for holding a stack of labels, a reciprocable arm for removing one label at a time from the stack, label-conveying means for receiving the removed label, label-positioning and holding means cooperating with the label-conveying means for holding the label in a predetermined position, means for moving a shook under the label-holding means, and including means for releasing the label-holding means from the label when the shook is in a position to receive the label, means for pressing the label down upon the shook, and means for holding the arm from removing a label from the stack until said shook-moving means is moving a shook to receive the label.

3. In a machine of the type described, a member for holding a stack of labels, a reciprocable arm having a label-engaging member for removing one label at a time from the stack, means for causing the arm to have its label-engaging

member engage the uppermost label when moved in one direction and said label-engaging member to be moved clear of the stack on the return movement of the arm, said means being adjustable for adjusting the stroke during which the label-engaging member of the arm contacts with the top label, whereby labels of different sizes may be handled.

4. In a machine of the type described, a member for holding a stack of labels, a reciprocable arm for removing one label at a time from the stack, a sleeve supporting the arm, a rod rockably supporting the sleeve, means for reciprocating the rod in a direction at right angles to its length, a cam designed to make one complete revolution for each complete reciprocation of the rod, a cam follower acted upon by the cam and having a cam track, and a cam track follower carried by the sleeve and being acted upon by the cam track for rocking the sleeve to lift the arm above the stack of labels during the return movement of the arm.

5. In a machine of the type described, a member for holding a stack of labels, a reciprocable arm for removing one label at a time from the stack, a sleeve supporting the arm, a rod rockably supporting the sleeve, means for reciprocating the rod in a direction at right angles to its length, a cam designed to make one complete revolution for each complete reciprocation of the rod, a cam follower acted upon by the cam and having a cam track, and a cam track follower carried by the sleeve and being acted upon by the cam track for rocking the sleeve to lift the arm above the stack of labels during the return movement of the arm, an abutment adjustably carried by the cam and constituting a portion of the cam periphery that acts upon the cam follower, said abutment being adjusted for altering the length of time the arm can contact the top label during the label-removing stroke of the arm, whereby the arm can remove labels of different sizes.

6. In a machine of the type described, a member for holding a stack of labels, a reciprocable arm for removing one label at a time from the stack, a tubular shaft secured to the arm, a shaft rockably supporting the tubular shaft, means for reciprocating the second shaft in a direction at right angles to the length of the shaft, a cam designed to make one complete revolution for each complete reciprocation of the rod, a cam follower acted upon by the cam and having a cam track, and a cam track follower carried by the sleeve and being acted upon by the cam track for rocking the tubular shaft to lift the arm above the stack of labels during the return movement of the arm, means for moving a shook into a position to receive a label removed from the stack of labels, and means for holding the cam follower in a position to keep the arm spaced above the stack of labels until a shook is received by the shook-moving means, whereby a label will be removed from the stack only when a shook is ready to receive it.

7. In a machine of the type described, label feeding means including an endless conveyor for receiving one label at a time, a label positioner and stop associated with the conveyor for holding a label in a predetermined position, means for feeding one shook at a time under the label positioner and stop and including means for moving said stop out of the way when the shook

reaches a position for receiving the label, said means also including a roller for pressing the label down upon the shook as the shook is moved.

8. In a machine of the type described, label feeding means including an endless conveyor for receiving one label at a time, a label positioner and stop associated with the conveyor for holding a label in a predetermined position, means for feeding one shook at a time under the label positioner and stop and including means for moving said stop out of the way when the shook reaches a position for receiving the label, said means also including a roller for pressing the label down upon the shook as the shook is moved and a second roller for contacting the label and shook for smoothing out any wrinkles.

9. In a machine of the type described, label feeding means including an endless conveyor for receiving one label at a time, a label positioner and stop associated with the conveyor for holding a label in a predetermined position, means for feeding one shook at a time under the label positioner and stop and including means for moving said stop out of the way when the shook reaches a position for receiving the label, said means also including a roller for pressing the label down upon the shook as the shook is moved, said label positioner and stop being adjustable to accommodate shooks of different thicknesses.

10. In a machine of the type described, means for holding a stack of labels, means for removing one label at a time from the stack, label-positioning and holding means cooperating with the label removing means for holding the label in a predetermined position, means for moving a member under the label-holding means and including means for releasing the label-holding means from the label when the member is in a position to receive the label, and means for pressing the label down upon the member for causing it to adhere thereto.

11. In a machine of the type described, means for holding a stack of labels, means for removing one label at a time from the stack, label-positioning and holding means cooperating with the label removing means for holding the label in a predetermined position, means for moving a member under the label-holding means and including means for releasing the label-holding means from the label when the member is in a position to receive the label, means for pressing the label down upon the member for causing it to adhere thereto, and means for preventing the label-removing means from removing a label from the stack until said member-moving means moves a member to receive the label.

MELVIN W. FLYNN.
